Atty.

UNITED STATES PATENT OFFICE.

LOUIS E. SLAUSON, OF ROCK ISLAND, ILLINOIS.

TRACTION WHEEL.

Application filed August 5, 1921. Serial No. 490,026.

To all whom it may concern:

Be it known that I, LOUIS E. SLAUSON, a citizen of the United States, residing at Rock Island, in the county of Rock Island 5 and State of Illinois, have invented certain new and useful Improvements in Traction Wheels, of which the following is a specification.

This invention relates to traction wheels 10 and one of the particular objects is to provide a structure in which the wheel is engaged with the shoes contacting with the ground in such a way that no slipping or spinning of the wheel can take place.

Another object of the invention is to simplify the construction by making the teeth by which the wheel engages the traction shoes part of the rim of the wheel.

Another object is to so construct the rim 20 of the wheel that it will present a smooth surface to the road when the track shoes have been removed and at the same time provide mounted engagement between the rim and the shoes to prevent any slipping.

In the accompanying drawings I have illustrated my invention in the form in which I have found it to be satisfactory in actual use, and referring thereto

Fig. 1 is a side elevation of my wheel with 30 a portion of the shoes removed.

Fig. 2 is an edge elevation of Fig. 1.

Fig. 3 is a perspective view of a track shoe and a tooth.

Fig. 4 is a transverse sectional view of 35 the wheel on the line 4—4 of Fig. 1.

The rim 1 of my wheel is composed of a pair of spaced annuli, preferably comprising angle bars 2 and a series of teeth 3 interposed between the annuli and held rigidly in place by the bolts or rivets 4. Each angle bar has one leg thereof disposed substantially radially of the wheel and the other leg thereof forms a tread to ride on the ground or on the traction shoes, as the case may be. One of these teeth is shown in the detail in Fig. 3 and it will be noted from the upper right hand portion of Fig. 1 that the curved faces of these teeth are substantially flush with the outer periphery 45 of the angle iron 2 thus presenting a rim surface that has no projections to sink into the road when the track shoes are removed. Each of these teeth is provided with a pair of upstanding ears 5 having the perforations

6 to receive pins 7 by which the shoes 8 are secured to the teeth. Each of the shoes includes a pair of track portions 9 connected by a plurality of cross pieces 10 one of which is preferably near the middle of the shoe and carries the standard 11 having the enlarged opening 12 to loosely receive the pin 7 when the standard 11 is located between the ears 5 of the particular tooth 3. Each end cross piece 10 is equipped with a post 13 adapted to lie between guides 15 carried by the opposite ends of each tooth whereby the shoes are limited in their torsional swinging about the loose connection with the teeth.

The cross pieces 10 adjacent to the ends of the shoes also extend inwardly to provide the ribs 16, the inner faces of which 17 are slightly curved to properly contact with the complementary end faces 18 of the teeth 3. The middle cross bar 10 also has an upstanding rib 19, the opposite faces of which are formed similar to the faces 17 for engagement with the walls 20 of a transverse recess 23 located about the middle of each tooth.

Projecting outwardly from each of the track sections 9 are a plurality of ground engaging bars 22 in this instance shown somewhat triangular in shape, adapted to sink into the ground and form the necessary driving engagement therewith.

From an examination of Fig. 1 it will be seen that when the wheel is driving in the direction indicated by the arrow the shoes are presented successively to the ground and form a practically continuous track on which the rim rolls evenly and the bars 22 bite into the ground and prevent the shoes from slipping relative thereto while the engagement between the surfaces 17 and 18 and 19 and 20 effectually gears the wheel to the shoes. Fig. 1 shows the parts in the relative position assumed when the axle is directly above the middle of a shoe, the ground being indicated by the line A, B. At the upper left hand portion of the figure I have shown two (2) shoes in the position assumed when the axle is directly above the space between the adjacent ends of two adjacent shoes, the dotted line C, D representing the ground. As the wheel rolls forward on a shoe G in Fig. 1 the descending shoe H drops, by virtue of the loose con-

nection with the pin 7 and the action of gravity, directly in front of the rim with its lower end adjacent to the front end of the shoe G. The proportions of parts are such that at the moment the wheel begins to put weight upon the shoe H it assumes a substantially horizontal position with all of the bars 22 engaging the ground, and the surface 18, which is marked K in Fig. 1, contacting with the surface 17, marked L, so that the driving engagement between the rim and the shoe is perfected without any slippage of the rim. As the wheel rolls forward on this shoe H the engagement is transferred successively from the leading end rib to the intermediate rib to the other end rib and then to the leading end rib of the next shoe.

The recess 3' is provided in each side of the tooth 3 to permit the escape of dirt which may be forced down between the ends of the cross pieces 10 and said sides.

It will be observed that pin 7 has a head at one end and an opening at the opposite end through which a cotterpin or other fastening device is passed. By this construction it is made possible to quickly remove all the shoes from the wheel upon coming to a piece of pavement or other surface over which toothed wheels are prohibited to travel and present a substantially smooth rim which will pass over the pavement without injuring it. Or in case it is desired to use some of the known forms of detachable lugs the shoes can be removed and the lugs attached directly to the face of the rim.

Another important feature that should be noted is that by providing the particular connection between the shoes and the teeth all the wear incident to the movement of the shoes comes against the teeth which are equally hard and which can readily be replaced by new castings when the wear has become excessive. The advantage of this is eliminating the wear on the rim sections, the replacement of which would be tantamount to building a new wheel.

I am aware that changes in the form and proportion and arrangement of parts of my invention may be made without departing from the spirit or sacrificing the advantages thereof and I therefore reserve the right to make all such changes as fairly fall within the scope of the following claims:

55 I claim:

1. In a traction wheel, a rim including a pair of side members, and intermediate tooth members, a traction shoe loosely pivoted to each of said tooth members and having driving surfaces adapted to be successively engaged by driving surfaces on said teeth.

2. In a traction wheel, a rim including a pair of side members and a series of intermediate members securing them together,

said intermediate members having driving faces adjacent to the ends and presenting outer surfaces substantially flush with said side members, a series of track shoes loosely pivoted to said intermediate members and having driving faces adapted to engage the driving faces on the intermediate members during the rotation of the wheel.

3. In a traction wheel, a rim including a pair of side members and a series of intermediate members secured thereto, each intermediate member presenting an outer face substantially flush with the side members and having a pair of bearing members and a pair of guides, traction shoes each having a portion adapted to be located between bearing members, means for loosely pivoting the traction shoes to said bearing members, and means carried by said traction shoes cooperating with the guides on the intermediate members to keep the shoes in alignment with the rim.

4. In a traction wheel, a rim including spaced side members and rigid intermediate connecting members, traction shoes loosely pivoted to said intermediate members, posts on said shoes and guides on said intermediate members cooperating with the posts to align the shoes in the direction of travel.

5. In a traction wheel, the combination of a rim including side members spaced by rigid intermediate teeth, traction shoes having means to engage with said teeth, means for loosely pivoting the shoes to the teeth, posts adjacent to the ends of the shoes, and spaced guides on the teeth receiving said posts.

6. In a traction wheel, the combination of a rim including spaced side members connected by intermediate members having transverse driving surfaces, a series of traction shoes loosely pivoted to said members, and means on said shoes to effect a driving engagement with said transverse driving surfaces on said members.

7. In a traction wheel, the combination of a rim including spaced side members connected by intermediate teeth having transverse driving surfaces, and a series of traction shoes loosely pivoted to the teeth and comprising spaced track members adapted to support said side members and intermediate ribs adapted to engage the teeth.

8. In a traction wheel, the combination of a rim including spaced rings connected by intermediate teeth, said teeth having pivot bearings adjacent to the middle and guides adjacent to the ends, and a series of shoes each having a standard pivoted to said bearings and posts cooperating with said guides.

9. In a traction wheel, the combination of a rim including spaced rings connected by intermediate teeth, each tooth having end bearing faces and intermediate bearing surfaces spaced by a transverse recess, and a

traction shoe loosely pivoted to each tooth and including spaced track members to support the rings, and transverse bars having teeth with bearing surfaces to cooperate with the bearing surfaces on the rim teeth.

10. In a traction wheel, a rim comprising spaced angle bars, teeth rigidly connecting said angle bars and substantially flush with

the outer surface of said rim and a traction shoe loosely and removably pivoted to each 10 of said teeth and provided with track portions for said angle bars and with means to engage said teeth to form a driving connection therebetween.

LOUIS E. SLAUSON.
